UNITED STATES PATENT OFFICE

RICHARD W. BURNETT, OF CHICAGO, ILLINOIS

RAILWAY HAND BRAKE

Application filed October 24, 1927. Serial No. 228,303.

My invention relates to a manually operated brake apparatus for railway cars and the principal object of the invention is to provide a simple and effective mechanism whereby the brakes of the car may be held in set position and released instantaneously and without reverse movement of the wheel or other element used for setting the brakes.

A further object is to so construct the releasing mechanism that the brake shoes may be either completely released from the wheels of the car or the pressure thereof relieved to a greater or less extent as may be desirable in switching cars and making up trains, in hump yards for example. With this operation in view, the invention provides means whereby the brakeman, with a minimum of danger to life and limb, may control the movement of the car by increasing or decreasing the pressures of the shoes on the wheels as may be necessary in order to bring the car gently and without violent collision against the car to which it is to be coupled in making up the train. Violent collisions between cars in the making up of trains, especially where the cars being handled glide down inclines, by gravity, have resulted very frequently in injury or death to brakemen and have also been the cause of great damage to cars and their contents due to impacts of the cars against each other and the shifting of their cargoes resulting from such impacts.

The present invention provides a new and improved hand brake apparatus having a hand wheel, or other manipulatable device, which the brakeman operates with one hand for creating the necessary pressure between the brake shoes and wheels of the car, and a lever, or like device, arranged near the hand wheel which can be operated with the same hand to relieve such pressure without any reverse movement of the hand wheel, the brakeman all the time being able to maintain with his other hand an uninterrupted hold on some fixed structure on the car.

The invention is illustrated in the accompanying drawings as forming part of a hand brake apparatus comprising a bellcrank arranged near, preferably under the floor of the car, a chain or other flexible connection between the bellcrank and said brake rigging, a substantially vertical rod for oscillating the bellcrank, a chain attached to the upper end of said rod and a drum on which the chain is wound; such combination of parts being disclosed in my copending application for hand brake mechanism filed May 14, 1926, Serial No. 109,061. The present invention, however, is not limited to this particular type of hand brake, which is shown herein merely for illustrative purposes, but is applicable to any hand brake apparatus utilizing a winding drum.

In the specification and claims the term "brake rigging" is intended to cover, as a whole, the apparatus under the flooring of the car for moving the brake shoes to and from the wheels of the car, this apparatus being ordinarily operated by air pressure. By the term "chain" I intended to cover any flexible connection capable of being wound on a drum.

The invention is illustrated in a preferred embodiment in the accompanying drawings wherein

Fig. 1 is a fragmentary side elevation, with parts in section, of a railway box car provided with the hand brake of my present invention.

Fig. 2 is a vertical sectional view of the mechanism, except for the hand wheel, employed for setting and releasing the brakes, this section being taken on line 2-2 of Fig. 4 but with the scale enlarged.

Fig. 3 is a fragmentary view showing the two manipulatable operating members of the brake apparatus with the housing for the gears, drum, et cetera, in the background.

Fig. 4 is a vertical sectional view through the housing and its enclosed mechanisms

taken on a plane parallel to the end of the car.

Fig. 5 is a fragmentary sectional view on line 5—5 of Fig. 3.

Fig. 6 is a detailed sectional view of a portion of the winding drum and associated parts of the mechanism, showing a modified construction.

Fig. 7 is a view in perspective of the sleeve employed for releasing the clutch between the winding drum and setting mechanism, and

Fig. 8 is a fragmentary view in perspective of the manipulatable brake releasing member.

Referring to the drawings, 10 designates the side wall, 11 the end wall, and 12 the flooring of a railway box car. The brake rigging, using that term as heretofore defined, is connected, for manual operation thereof, by means of a chain 13 to a bell-crank 14, pivoted at 15 to the under side of the car and formed with an operating arm 16, to which is connected a substantially vertical rod 17, this connection being preferably formed by a pin 18 extending through an elongated slot 19 in the operating arm. Attached to the upper end of the rod 17 is a chain 20 which is adapted to be wound on a drum 21. The drum is preferably eccentric for the purpose indicated in the copending application above referred to but my present invention is not concerned with this feature of the apparatus. The drum may be of any suitable contour.

The drum is arranged in a housing on the end wall of the car consisting preferably of a backplate 22 and a front housing member 23 suitably secured together. The drum 21 is slidably arranged on a fixed shaft 24 secured by a head 25 to the backplate 22 and projecting through the front member of the housing. Revolvably mounted on the shaft 24 is a gear wheel 26 and, on the other side of the drum, a sleeve 27 (Fig. 7). Preferably bronze bushings 28, 29, and 30 surround shaft 24, intervening between the gear wheel 26, drum 21 and sleeve 27. The gear wheel is formed near its perimeter with a recessed friction surface 31 against which is seated a radially severed clutch ring 32. Secured to the friction ring 32 are a suitable number of struts designated 33, two being shown, these struts being pivoted (Fig. 2) to a drum by pins 34; or the ends of the struts, in this case designated 33^a, being merely seated (Fig. 6) in recesses 34^a in the drum. In either case slight movement of the drum in the direction toward the end of the car (to the right, Figs. 2 and 6) will bring about a clutched engagement between the drum 21 and gear wheel 26. This clutched relationship is maintained normally by means of a heavy coiled spring 35 which intervenes between a wear plate 36 on the front housing member 23 and a collar 37 which is screwed on the end of the sleeve 27. The sleeve 27 projects through the front wall of the casing and is provided with an oblique

arranged head. A lever 39, normally under stress of a coiled spring 39^a and having an operating handle 40, is pivoted to the front wall of the casing by means of a shouldered and riveted stud 41. The lever 39 has a wedge shaped portion 42 adapted to intervene between the oblique head 38 of sleeve 27 and the front wall of the casing, this portion of the lever being formed with a slot 43 through which the sleeve 27 projects and with a curved rib 44 to engage one edge of the head. By raising the lever, (see Fig. 3) spring 35 is compressed so as to release the hold between friction ring 32 and the friction surface 31 of the gear wheel. This permits the pressure of the brake shoes against the wheels of the car to be relieved, either completely or partially, and either instantaneously or gradually.

Meshing with gear 26 is a gear 45 formed on the shaft 46 of a hand wheel 47, shaft 46 turning in bearings 48, preferably with the interposition of bronze bushings 49, in the front and back housing members 22, 23. On shaft 46 is a ratchet wheel 50 engaged by a detent 51 pivotally mounted on a shaft 52 extending across the upper end of the housing, the ends of which are shouldered and riveted to the housing members. Preferably a coiled spring 53 is arranged between the upper flange 54 of housing member 23 and the nose of the detent, which latter is formed with a centering stud 55 for the spring.

Preferably a platform 56 for the brakeman is secured to the end wall of the car 11 at a suitable distance below the housing 22—23.

Operation.—The brakeman, standing on platform 56, sets the brakes by rotating the hand wheel 47 in the clockwise direction using his right hand. The friction of the parts of the apparatus is so small that the slack in the brake apparatus, including the necessary slack in the brake rigging under the car, may be taken up and the brake shoes brought against the wheels of the car with considerable pressure by the initial operation of the hand wheel. If additional pressure is required a new hold may be taken on the wheel, either at the rim or one of its spokes. During this operation the brakeman can steady himself by taking hold with his left hand of one of the adjacent rungs of the end ladder with which most box cars are provided or of the roof hand hold, or, in case of gondola cars, of the upper edge of the car end. To release the brakes the brakeman, maintaining his left hand hold on the end ladder rung hand hold or the like, raises lever 39 by grasping its handle 40 with his right hand. A quick pull up on the lever will instantaneously bring about the release of all pressure of the shoes on the wheels of the car but if a gradual or partial release is desired the lever may be raised just sufficiently to permit a slip between the clutch ring 32 and the friction surface 31 of

gear wheel 26. The hand wheel remains stationary, being effectively dogged by the engagement of detent 51 with the ratchet wheel 50. If control of the car requires increase of pressure, the hand wheel may be turned to a greater or less extent, and thus by this easy and safe manipulation of the wheel 47 and the lever 39 the velocity of the car may be accurately controlled. At all times the 10 brakeman maintains his left-hand hold on a fixed part of the car. The brake is a one hand brake. The left hand need not be used in any part of the operation of the brake.

15 It is realized that the brake apparatus herein shown and described may be changed considerably without departure from the scope of the invention. Therefore I wish it to be understood that the invention includes all 20 modifications within the language of the appended claims.

The winding mechanism and vertical wheel in combination with the bellcrank; the housing construction; the bellcrank construction; 25 and the configuration of the winding drum are not claimed herein apart from the other arrangements and constructions herein shown and claimed. The said general combination of winding mechanism and bellcrank and the 30 other improved constructions above noted are claimed in the order above named in my co-pending applications as follows: Serial Nos. 109,061, filed May 14, 1926 and 349,817, filed March 25, 1929; 329,243, filed December 29, 35 1928; 560,407, filed August 31, 1931; and 349,818, filed March 25, 1929.

I claim:

1. In combination with the brake rigging of a railway car, means for setting the brakes 40 comprising a chain, a drum on which the chain is wound, a shaft on which the drum is slidably mounted, mechanism for rotating the drum in the direction to set the brakes comprising a revolute element and detent 45 means for the same, a friction ring bearing against said revolute element and struts extending from said drum to said ring providing a clutch between said drum and revolute element, and mechanism for moving said drum lengthwise of the shaft for controlling the operation of the clutch.

2. In combination with the brake rigging of a railway car, means for setting the brakes 55 comprising a chain, a drum on which the chain is wound, a shaft on which the drum is slidably mounted, mechanism for rotating the drum in the direction to set the brakes comprising a revolute element and detent means for the same, and a clutch between said 60 drum and revolute element comprising a friction ring bearing against the revolute element, struts extending from the drum to the ring, a spring bearing against the drum to normally maintain engagement between 65 the ring and revolute element, a sleeve on

said shaft for compressing the spring to release the clutch, and a revolute wedge for moving the sleeve lengthwise of the shaft.

3. In combination with the brake rigging of a railway car, means for setting the brakes 70 comprising a chain, a drum on which the chain is wound, a shaft on which said drum is slidably mounted, a gear on said shaft, a clutch interposed between the drum and gear, a spring normally maintaining the clutch in operative engagement with the drum and gear, means for compressing the spring to release the gear, a hand wheel having a shaft 75 parallel to the drum shaft, a gear on the hand wheel shaft meshing with the gear on the drum shaft, a ratchet on the hand wheel shaft, and a detent to engage said ratchet.

4. In combination with the brake rigging of a railway car, means for setting the brakes 80 comprising a chain, a drum on which the chain is wound, a shaft on which said drum is slidably mounted, a gear on said shaft, a clutch interposed between the drum and gear, a spring normally maintaining the clutch in operative engagement with the drum and 85 gear, means including a lever for compressing the spring to release the gear, a hand wheel parallel with the lever having a shaft parallel to the drum shaft, a gear on the hand wheel shaft meshing with the gear on the drum shaft, a ratchet on the hand wheel shaft, and a detent to engage said ratchet.

5. In combination with the brake rigging of a railway car, a chain for moving the same 90 to set the brakes a bell-crank to which the chain is attached, a substantially vertical rod for rocking the bell-crank, a chain on said rod, a vertically disposed housing on the end of the car, a vertically disposed hand wheel having a shaft extending through the upper portion of the housing, a ratchet wheel and a gear on said shaft, a detent to engage the ratchet wheel, a fixed shaft extending through the lower part of the housing, a gear 95 revolute on said lower shaft meshed with the gear on the hand wheel shaft, a drum 100 slidably on said lower shaft on which said second named chain is adapted to be wound, a clutch interposed between said drum and the gear on the lower shaft, and a lever pivoted to the end of the housing for controlling 105 said clutch.

6. In combination with the brake rigging of a railway car, a chain for moving the same 110 to set the brakes, a bell-crank to which the chain is attached, a substantially vertical rod for rocking the bell-crank, a chain on said rod, a vertically disposed housing on the end of the car, a vertically disposed hand wheel having a shaft extending through the upper portion of the housing, a ratchet wheel and a gear on said shaft, a detent to engage the ratchet wheel, a fixed shaft extending 115 through the lower part of the housing, a gear revolute on said lower shaft meshed with the 120 gear on the hand wheel shaft.

gear on the hand wheel shaft, a drum slidable on said lower shaft on which said second named chain is adapted to be wound, a clutch interposed between said drum and the gear 5 on the lower shaft, a sleeve on said lower shaft provided with a collar, a spring bearing against said collar to normally maintain the clutch in its engaging position, a head on the outer end of the sleeve, and a controlling lever 10 pivoted to the casing having a wedge adapted to bear against said head to impart longitudinal movement to the sleeve in the direction to compress said spring and release the clutch.
